US0D1095314S

(12) **United States Design Patent** (10) Patent No.: **US D1,095,314 S**
(45) Date of Patent: ** Sep. 30, 2025

(54) **CAULDRON**

(71) Applicant: **Dongguan Aidong Intelligent Technology Co., Ltd.**, Dongguan (CN)

(72) Inventor: **Haojie Zhao**, Beijing (CN)

(73) Assignee: **DONGGUAN AIDONG INTELLIGENT TECHNOLOGY CO., LTD.**, Dongguan (CN)

(**) Term: **15 Years**

(21) Appl. No.: **29/906,366**

(22) Filed: **Nov. 3, 2023**

(51) LOC (15) Cl. **11-05**

(52) U.S. Cl.

USPC **D11/121**

(58) **Field of Classification Search**

USPC D11/117, 125, 131, 143, 148, 157, 184;

D21/525; D7/354, 360

CPC A47G 19/12; A47G 19/30; A47G 7/06;

A47J 27/00
